UNITED STATES PATENT OFFICE

161,016

SLIP

Samuel Godfried, New York, N. Y., assignor to Godfried Underwear Co., Inc., New York, N. Y., a corporation

Application March 8, 1949, Serial No. 1,280

Term of patent 3½ years

(Cl. D3—26)

To all whom it may concern:

Be it known that I, Samuel Godfried, a citizen of the United States of America, and a resident of the city of New York, in the county of New York and State of New York, have invented a new, original, and ornamental Design for a Slip, of which the following is a specification, reference being had to the accompanying drawing, forming a part thereof:

Fig. 1 is a front view of a slip showing my new design, and

Fig. 2 is a rear view thereof.

I claim:

The ornamental design for a slip, substantially as shown.

SAMUEL GODFRIED.
